UNITED STATES PATENT OFFICE

RALPH H. CHURCHILL, OF CHICAGO, ILLINOIS

HEAT-CONDUCTING SYSTEM

No Drawing.

Application filed November 15, 1926. Serial No. 148,612.

The purpose of this invention is to provide a heat-conducting system which includes a radiator connected in a circulatory system and a heat conducting medium 5 adapted for circulation through such radiator and composed of material which will not freeze at any expected winter temperatures and will remain sufficiently mobile at low temperature to circulate readily. Such

10 a medium is particularly well adapted to serve as a cooling element for an internal combustion engine, especially in an automotive vehicle, though obviously its usefulness is not confined to this class of work. 15 The invention consists in certain elements or ingredients combined as hereinafter described and as indicated in the claims.

As is well understood, the water commonly employed in a circulatory system 20 used for cooling an internal combustion engine, as in an automobile or aeroplane, will freeze at ordinary winter temperatures, and heretofore it has been common practice to add a certain proportion of alcohol 25 to the water to lower the freezing point or to use glycerine for the same purpose. The alcohol has the disadvantage of evaporating readily and thus separating from the water, leaving a mixture of unknown 30 properties whose freezing point is constantly rising as the alcohol is gradually eliminated; glycerine, on the other hand, while it does not evaporate readily, is comparatively expensive, and is not a particularly good conductor of heat. It is also 35 well known that mineral oils, including various grades of petroleum, have a low freezing point, a high boiling point, and can be circulated readily enough in a cooling system, but they are also poor conductors of heat, and the use of any such oil alone would tend to permit undesirably high temperatures for the operation of an engine.

This invention undertakes to employ an 40 oil such as kerosene or other thin petroleum product which is preferably cheaper than glycerine as the principal circulating element, but compensates for its poor heat-conducting qualities by providing a quantity of finely-divided material distributed

through the oil and carried more or less in suspension therein. By experiment I have found that finely-divided aluminum is quite effective for this purpose, since its heat conductivity is relatively high and its presence in fine particles in the oil assists in the rapid absorption of heat from the cylinder walls of the engine and in the equally effective radiation of the heat when the cooling medium reaches the radiator. 60

It will be evident to those skilled in the sciences of chemistry and physics that other solid materials than aluminum may be employed. For example, magnesium in finely divided form would also be satisfactory, except that it is less plentiful and therefore more expensive than aluminum. Of the metals, it will be understood that the relatively lighter ones are preferred because they are more effectively held in suspension 70 in the liquid.

However, where it is necessary to keep the liquid somewhat agitated and in constant circulation in order to maintain proper distribution of the finely-divided metal 75 through the liquid vehicle, this is accomplished in the usual cooling system by means of a circulating pump which operates whenever the engine is running, but when the engine stops and the pump ceases to 80 work, there may be a tendency for the metal particles to settle through the oil to the lower points in the system or into any pockets which may be present in the cylinder jackets of the engine. Being very finely divided, the metallic particles will then tend to pack as they settle, so that they will not be readily taken up by the liquid when the circulation is resumed. I have discovered, however, that by adding to the oil 85 a small quantity of glycerine or sugar solution or honey, or perhaps some other liquid substance of greater density than the oil itself, the packing of the metal may be prevented because the glycerine or other heavy 90 liquid settles through the oil more rapidly than the metal and fills the low points of the system and the pockets in which the metal would tend to accumulate thus forming a fluid coating for the walls of the jack-

100

ets and conduits of the system at these low points which prevents the metallic particles from adhering to the walls and allows them to be readily stirred up and re-distributed through the oil whenever the circulation of the latter is resumed.

Preferably the aluminum or other solid material used as the heat-conducting medium, should be in the form of extremely thin flakes which is the form in which aluminum is commonly prepared for use in paint; this obviously exposes a maximum area for the absorption and radiation of heat, and also provides a material which will remain longer in suspension in the liquid vehicle because the flat form of the flakes serves to retard their fall through the liquid if there is a tendency for them to settle.

20 I claim:—

1. A heat conducting medium comprising a quantity of aluminum in finely divided form and a relatively thin oil serving as a vehicle for said aluminum, together with 25 a quantity of glycerine intermingled therewith and adapted to settle when the mixture is at rest.

2. A heat-conducting medium comprising a quantity of aluminum in the form of 30 minute flat flakes and a relatively thin oil serving as a vehicle therefor, together with a quantity of glycerine intermingled therewith and adapted to settle more readily than the flakes of aluminum when the mixture is at rest.

3. A heat-conducting medium comprising a quantity of aluminum in finely divided form, a relatively thin oil serving as a vehicle therefor, and a liquid of greater density than the oil, said ingredients being 40 intermingled normally, with the aluminum substantially carried in suspension, the heavier liquid being adapted to separate from the oil and settle more readily than the aluminum when the mixture is at rest.

4. A heat-conducting medium comprising a quantity of aluminum in finely divided form and a relatively thin oil serving as a vehicle for said aluminum.

50 5. A heat-conducting medium comprising a quantity of a relatively light metal in finely divided form and a relatively thin oil serving as a vehicle therefor.

6. A heat-conducting medium comprising 55 a quantity of a relatively light metal in finely divided form and a thin mineral oil serving as a vehicle therefor.

7. A heat-conducting medium comprising a quantity of a relatively light metal in the 60 form of minute flat flakes and a relatively thin oil serving as a vehicle therefor.

8. A heat-conducting medium comprising a quantity of a relatively light metal in finely divided form and a relatively thin 65 oil serving as a vehicle therefor, together

with a liquid of greater density intermingled therewith and adapted to settle more rapidly than the metal when the mixture is at rest.

In testimony whereof, I have hereunto set my hand at Chicago, Illinois, this 12th day of November, 1926.

RALPH H. CHURCHILL.
